UNITED STATES PATENT OFFICE

ABRAHAM H. ZUCKER, OF CLEVELAND, OHIO

SCRUBBING MACHINE

Application filed May 11, 1928. Serial No. 277,024.

The objects of the invention are to provide an improved floor scrubbing machine, that is operated by means of an electric motor which accompanies the machine and which is so designed as to operate the scrubbing brushes in a direction transverse to the forward movement of the machine, and thus develop as much friction as possible upon the floor as the machine is propelled thereover.

Further objects of the invention are to provide a multiple number of small brushes which are resiliently supported in a common bar that is reciprocated transversely of the machine, thus permitting the brushes to accommodate themselves to an uneven floor surface and to perform the work much more efficiently than if larger brushes were employed that would each cover more floor surface.

To accomplish these and other valuable objects the invention is illustrated in the accompanying drawings, hereinafter more fully described, and particularly pointed out in the claims.

In the accompanying drawings, Fig. 1 is a plan of the device, Fig. 2 is a front elevation thereof, Fig. 3 is a side elevation thereof, Fig. 4 is a transverse section of one of the reciprocating bars, bronze bearings and supporting bar, and of the perforated supply pipe for cleaning fluid. Fig. 5 is an end elevation of a brush showing means for attaching it to a reciprocating bar.

In these views A is the frame, B is an electric motor therein which may be connected with any convenient socket or floor plug.

C, C' are rigid transverse bars connecting the sides of the frame, and D, D' are channel bars reciprocable upon the rigid bars C, C', respectively, in bronze bearings E, E' thereon.

The motor B is operatively connected with the reciprocable bars D, D', by means of speed reducing gearing such as the pinion A, B' and spur gear F, a crank shaft G, cranks H, H' thereon and connecting rods I, I' respectively, and wrist pins J, J' which pass through slots K in the rigid transverse

bars C, C' and bearings thereon, as shown in Fig. 4.

The brushes L are mounted detachably in metal backs M, provided with spaced vertical rods, N, N, that pass through the vertically spaced upper and lower flanges D², D³ of the reciprocatable bars D, D'.

The rods N, N, slide freely in these bars and the brushes are resiliently pressed against the floor by means of springs D⁴, D⁴ enclosed in the space between the flanges D², D³ and resting on shoulders N' upon the rods.

The rods may be cast in the metal backs M, or screwed therein if desired.

P, P, are horizontal metal pipes perforated at P' for supplying a cleaning fluid stored in the tank Q to the floor in advance of the brushes where it will be of the greatest use.

These pipes are connected with the tank above by means of vertically extending flexible pipes R, R, controlled by means of a valve S to permit the pipes P to reciprocate with the bars D, D'.

The pipes P' are secured to the reciprocable bars by means of rigid arms T, T.

At V is shown a rubber squeegee that traverses the floor in the rear of the brushes, and collects the soiled suds or cleaning fluid in the corner formed at the junction of two converging walls, thus preventing it from spreading over the floor.

This collection of soiled fluid is then taken up by means of a suction hose W, and suction pump W' and deposited in a separate tank W² at the rear of the machine.

The squeegee V is mounted upon a frame V' of corresponding shape which is resiliently guided upon vertical rods V² that are movable in the frame above, springs V³ press the squeegee resiliently against the floor.

Having described the invention what I claim as new and desire to secure by Letters Patent is,

1. In a floor scrubbing machine in combination, a frame, longitudinally spaced rigid bars transversely secured across said frame, brush holding bars, spaced bearings

on said rigid bars in which said brush holding bars are movable, said brush holding bars being provided with vertically spaced flanges, brushes underneath each brush holding bar, each brush being provided with vertical rods passing through said spaced flanges, and springs upon said rods, said rods having shoulders thereon, said springs being confined between the upper one of said flanges and said shoulders.

10 2. In a floor scrubbing machine in combination, a frame, longitudinally spaced rigid bars transversely secured across said frame, brush holding bars, spaced bearings

15 on said rigid bars in which said brush holding bars are movable, said brush holding bars being provided with vertically spaced flanges, brushes underneath each brush holding bar, each brush being provided with vertical rods passing through said spaced

20 flanges, and springs upon said rods, said rods having shoulders thereon, said springs being confined between the upper one of said flanges and said shoulders, and means for reciprocating said brush holding bars.

25 3. In a floor scrubbing machine, a frame, rigid bars transversely secured across the lower part of said frame, spaced bearings on said rigid bars and brush holding bars reciprocable in said bearings, a motor and a crank shaft, and connecting rods, wrist pins connecting said brush holding bars, and said connecting rods, said bearings and rigid bars being provided with openings for the passage of said wrist pins.

35 4. In a floor scrubbing machine, in combination a frame, a rigid transverse bar thereon adjacent to its lower edge bearing thereon, a brush holding bar reciprocable in said bearings, said bar being provided with vertically spaced flanges, a multiple number of brushes underneath said bar, each brush being provided with a pair of rods vertically movable in the spaced flanges in said brush holding bar, and springs upon said rods, said springs being confined between the said spaced flanges, said rods having shoulders upon which said springs rest.

50 5. In a floor scrubbing machine, a frame, rigid transverse bars and bearings thereon, a bar having vertically spaced flanges and reciprocable thereon, a multiple number of brush holding members thereunder, a pair of rods secured to each of said brush holding members and vertically movable in said flanges and springs upon said rods, said rods being provided with shoulders, said springs being confined between the upper one of said flanges and said shoulders.

60 6. In a floor scrubbing machine, a frame, a pair of bars rigidly secured transversely of the machine and spaced apart therein, bearings thereon, a brush holding bar reciprocable in the bearings in each transverse bar, a multiple number of brushes under-

neath each reciprocable bar, brush holders therefor, vertical rods secured to said brush holders and movable in vertically spaced bearings in said brush holding bars, and means for reciprocating said brush holding bars transversely of said frame.

70 In testimony whereof I affix my signature.

ABRAHAM H. ZUCKER.
